Patented Feb. 8, 1916.

UNITED STATES PATENT OFFICE.

SAMUEL BUYER, OF NEW YORK, N. Y.

HOSE-SUPPORTER.

1,170,875.

Specification of Letters Patent.

Patented Feb. 8, 1916.

Application filed February 27, 1915. Serial No. 10,913.

To all whom it may concern:

Be it known that I, SAMUEL BUYER, a citizen of the United States of America, residing at New York city, Manhattan borough, county and State of New York, have invented certain new and useful Improvements in Hose-Supporters, of which the following is a full, clear, and exact description.

This invention relates to an improvement 10 in hose-supporters, but pertains more particularly to a fastening device therefor, said fastening device being used to secure the web of the supporter and pad together.

One of the chief features of the invention 15 is to provide a fastener that will securely bind the web and pad or other parts together without the necessity of employing teeth or other sharp projections that will eat into the fabric or webbing, thereby in time weakening same.

A further feature of the invention is to provide means to protect the hosiery, under-wear or flesh from the metal fastener.

I will now proceed to describe my invention in detail, the novel features of which I 25 will point out in the appended claims, reference being had to the accompanying drawing, forming part hereof, wherein—

Figure 1 is a sectional view on a large 30 scale of my improved fastener and a portion of a hose supporter, the section being taken on a line 1—1 in Fig. 2; Fig. 2 is a top plan view thereof; Fig. 3 is a cross-sectional view, the section being taken on a line 3—3 in 35 Fig. 1; and Fig. 4 is a plan view of the blank out of which my improved fastener is made.

My improved fastener consists of a plate A bent over upon itself to form a jaw 1. When bent over the fastener will consist of 40 the jaw members 2 and 3, the wall member 3 being provided with wings 4 (Fig. 4) to finally form clip 5 by which means the fabric or elastic members of the supporter are secured in connection with retaining means 45 which I will now describe.

To coöperate with the clips 5, I provide securing means consisting of a recess 6 in the member 2 of the fastener and a projection 7 carried by the member 3 of the fastener. The rounded end 8 of the jaw 1 retains one end of a link 9 and through the eye of the link, and over the opposite end thereof, I carry one member 10 of the protecting medium which forms part of my invention. 5 The web or elastic member of the supporter is indicated by 11 and the pad by 12, the fas-

tener A connecting the said web and pad. The weakest part of a hose-supporter is usually at the point 13 at which point the fastener is usually supplied with teeth that eat 60 into the fabric. One of the objects of this invention is to obviate the necessity of using these teeth or sharp edges, and I do so by providing the recess 6, projection 7 and clips 5.

By referring to Fig. 1 it will be seen that one end of the web 11 and the doubled over end 14 of the protector 15 are held in the jaw 1. The free ends 16 of the protector are sewed between the members 17 and 18 of the pad 12. As has been stated, one member 10 of the protector passes over the end 19 of the link 9, while the other member 20 of the protector passes under said end 19. As the surface B of the pad is the bottom, or the portion which contacts with the hosiery, the metal of the fastener A and also the link 9 is kept out of contact with the flesh or under-wear by the member 20 of the protector. The double protector provides sufficient 80 thickness under the protector A to withstand considerable wear.

To apply the fastener, I place the end of the web 11 and the doubled over end of the protector between the fastener members 2 and 3 and also over the projection 7 and under the recess 6. I then bend upwardly the wings 4 to lie against the edges of the members 11 and 15 (Fig. 3), and finally I bend downwardly the ends of said wings 4 as shown in Fig. 3 and press the mass together by applying considerable pressure, after which the projection 7 will press the fabric members firmly together and into the recess 6, after which they cannot be pulled out and there will not be any teeth or sharp edges to cut the fabric. The link 9 stiffens the connection between the fastener and protector, that is to say, it prevents any side-play on the part of the fastener relative to the protector.

Having now described my invention, what I claim and desire to secure by Letters Patent is:

1. A fastener for hose-supporters, consisting of a plate bent over upon itself to form a jaw, coöoperating fastening means carried by the jaw-members of said fastener, and located intermediate the ends thereof, arranged to coöperate one with the other, clips carried by one jaw-member arranged to engage the other jaw-member,

- said clips being located between the fastening means and the free ends of said jaw-members, a link engaged at one end thereof by said fastener, and a protector, consisting of a strip of fabric doubled upon itself, one member of said protector passing through said link and over the free end thereof, the other protector member passing under said link, both protector members passing under said fastener, the doubled over end of said protector being engaged by said fastener.
2. In combination with a hose-supporter fastener, a link secured, at one end thereof, to said fastener, and a protector consisting of a strip of fabric doubled upon itself, one member of said protector passing through said link and over the free end thereof, the other protector member passing under said link, both protector members passing under said fastener, the doubled over end of said protector being engaged by said fastener.

3. In combination with a hose-supporter having an elastic webbing and a pad, a protector consisting of a strip of fabric doubled upon itself, the free ends being secured to said pad, a fastener consisting of a strip of metal turned over upon itself to form a jaw, the doubled over end and one end of said webbing being located within the jaw of the fastener, one member of said jaw being provided with a recess, a projection carried by the other jaw-member alining with said recess to force said webbing and protector together, and clips carried by one jaw-member arranged to engage the other jaw-member and bind said members together.

Signed at New York city, N. Y., this 24 day of February, 1915.

SAMUEL BUYER.
